(57) **CLAIM**

(**) Term: **14 Years**

The ornamental design for a backguard/control panel for a cooking appliance, as shown and described.

(21) Appl. No.: **29/191,467**

DESCRIPTION

(22) Filed: **Oct. 9, 2003**

FIG. 1 is an upper right perspective view of our new backguard/control panel design for a cooking appliance; FIG. 2 is an enlarged, upper right perspective view of the backguard/control panel of FIG. 1;

(51) LOC (8) Cl. **07-02**

FIG. 3 is a front elevational view of the backguard/control panel of the invention;

(52) U.S. Cl. **D7/406**

FIG. 4 is a top view of the backguard/control panel of the invention; and,
